CLAIM

The ornamental design for a toy organizer, as shown and described.

DESCRIPTION

FIG. 1 is a perspective view of a toy organizer;

FIG. 2 is a front elevational view thereof;

FIG. 3 is a back elevational view thereof;

FIG. 4 is a first side elevation view thereof;

FIG. 5 is a second side elevation view thereof;

FIG. 6 is a top plan view thereof; and,

FIG. 7 is a bottom plan view thereof.

The cross-hatch shading depicts a woven fabric texture which is fragmentarily shown in the figures but is understood to repeat uniformly and continuously across the entire indicated surface areas.
